UNITED STATES PATENT OFFICE

163,362

GIRDLE OR SIMILAR ARTICLE

Alfred Brown, New York, N. Y.

Application July 21, 1950, Serial No. 11,288

Term of patent 14 years

(Cl. D20—2)

To all whom it may concern:

Be it known that I, Alfred Brown, a citizen of the United States of America, residing in New York city, county of Kings, and State of New York, have invented a new, original, and ornamental Design for a Girdle or Similar Article, of which the following is a specification, reference being had to the accompanying drawing, forming part thereof, wherein,

I claim:

The ornamental design for a girdle or similar article, substantially as shown.

ALFRED BROWN.
